UNITED STATES PATENT OFFICE.

JOHN WRIGLEY, OF ELMIRA, NEW YORK.

RAILWAY-SIGNAL.

SPECIFICATION forming part of Letters Patent No. 663,990, dated December 18, 1900.

Application filed June 30, 1900. Serial No. 22,132. (No model.)

To all whom it may concern:

Be it known that I, JOHN WRIGLEY, a citizen of the United States, residing in Elmira, in the county of Chemung and State of New York, have invented certain new and useful Improvements in Railway-Signals; and I do hereby declare the following to be a full, clear, and exact description of the invention, such as will enable others skilled in the art to 10 which it appertains to make and use the same, reference being had to the accompanying drawings, and to letters of reference marked thereon, which form a part of this specification.

15 This invention relates to semaphore apparatus employed in railroad signaling; and it has reference particularly to that class of such apparatus in which revolving lamps are employed for night signaling.

20 The object of the invention is to provide an apparatus of the kind referred to with simple and durable means whereby the lamp thereof may be operated with facility and positively.

I have fully illustrated my invention in the 25 accompanying drawings, wherein—

Figure 1 is a view in front elevation of my improved semaphore apparatus. Fig. 2 is a side view, in side elevation, of a portion of the operating mechanism for the lamp somewhat 30 enlarged. Fig. 3 is a top plan view of substantially what is shown in Fig. 2. Fig. 4 is a vertical sectional view, still further enlarged, of the lower portion of the mechanism shown in Fig. 2; and Figs. 5 and 6 are a top 35 plan view and a sectional view of a detail of the invention.

a in the accompanying drawings designates the mast or pole upon which the semaphore apparatus is mounted. *b*, *c*, and *d* designate 40 three brackets, which are suitably secured to said mast.

e designates a balance-lever which is fulcrumed upon the bracket *c*. This lever is adapted to be controlled by wires or other 45 flexible connections extending to the operating-tower, and it is balanced by an adjustable weight *f*.

Upon the bracket *b* is fulcrumed a lever *g*, which carries the signaling-paddle *h* and also 50 an adjustable counterbalance-weight *i*.

In the arm *j* of the bracket *d* is journaled a vertical shaft *k*, said shaft carrying at its

upper end a seat or rest *l* for the lamp *m* of the apparatus. Upon this shaft is secured by a pin *n* an elongated segment *o*, having a curved slot *p*, the extremities *q* of which are straight, extending longitudinally thereof. The lower end of this segment has bearings upon the lower arm *j* of the bracket *d*, and therefore supports the shaft *k*. Figs. 5 and 6 show this segment in elevation and transverse section. In order to prevent freezing water from collecting in the bearing for the shaft *k* in the upper arm *j*, I provide a collar *r*, having a recess *s* in its under side, being 65 adjustably secured upon the shaft and acting as a hood for said bearing, said recess receiving a boss *t* upon the upper face of the arm. The slotted segment constitutes a cam which is controlled by a slide-rod *u*, which is 70 adapted to reciprocate vertically in projections *v* of the arms *j*, being provided with a stud *w*, upon which is mounted an antifriction-roller *x*, which works in the slot *p*.

y designates a rod which is pivotally connected at its ends to the levers *g* and *e*, respectively, and *z* designates another rod, which is connected at its ends to the slide-bar and said lever *e*, respectively. Should the rod *y* have a greater range of movement than the 80 rod *z*, as will doubtless usually be the case, the latter may be provided with a slot *a'* at either of its ends, receiving the pivoting-pin at this point, as shown in Fig. 1. However, if desired, the lower end of the rod *z* may be 85 turned off and connected to the rod *y*, as shown at *a'* in the same figure, in which case it will not be necessary to provide the compensating slot *a'*.

In operation when the lever *e* is thrown 90 from one to the other of its limits of movement a corresponding movement will be imparted to the lever *g* carrying the paddle, while the slide-rod *u* will be moved longitudinally in its bearings, the antifriction-roller 95 which it carries working in the cam-slot *p* and so turning the segment *o*, and consequently the shaft *k* carrying the lamp. The movement of the lever *e* in the other direction will of course effect a reverse movement 100 of these parts. Should the lamp in any way become disconnected with the lever *e* while it is held at safety, the slide-rod will be actuated by gravity to drop and so throw the

lamp to the danger position, and of course should the rod z be directly connected to the rod y the paddle h may also be made to be controllable in like exigency by the slide-rod, so as to be thrown to the danger position.

It has been remarked that the extremities g of the slot p are straight. The object of this is to afford compensation for the difference in time which it takes the paddle to assume its limit of movement and the time which it takes the lamp to assume its limit of movement and resulting from the form of connection between them and their operating means, the lamp being arranged to move more quickly than the paddle. Moreover, said straight extremities of the slot act, as will be obvious, to prevent the lamp from being turned, whether accidentally or otherwise, except through the medium of the slide-rod u , having the projection engaging said slot p . The importance of providing this compensating and locking medium will be manifest to those familiar with this art.

Having thus fully described my invention, what I claim as new, and desire to secure by Letters Patent, is—

1. The combination, with a suitable support, of a rotary lamp-carrying device and a suitably-guided slide-rod operatively arranged on said support and the one having a cam-slot, and the other a projection engaging said slot, actuating mechanism, and a paddle-carrying lever fulcrumed on said support, said slide-rod and the other being operatively connected to said actuating mechanism, substantially as described.

2. The combination, with a suitable support, of a rotary lamp-carrying device operatively arranged on said support and having a cam-slot, a suitably-guided slide-rod having a projection engaging said slot, a paddle-car-

rying lever fulcrumed on said support, and actuating mechanism, said lever and the slide-rod being operatively connected to said actuating mechanism, substantially as described. 45

3. The combination, with a suitable support, of a bracket sustained on said support and having laterally-projecting arms disposed the one above the other, a rotary lamp-carrying device and a slide-rod arranged in said arms and the one having a cam-slot and the other a projection engaging said cam-slot, and actuating mechanism also arranged on said support, said slide-rod being operatively connected to said actuating mechanism, substantially as described. 55

4. The combination, with a suitable support, of a bracket sustained on said support, a segment and a slide-rod arranged in said bracket and the one having a cam-slot and the other a projection engaging said cam-slot, said segment being sustained by the bracket, a shaft for the segment journaled in said bracket, said shaft constituting the lamp-support, and means for actuating said slide-rod, substantially as described. 65

5. The combination, with a suitable support, of a bracket sustained on said support, a segment sustained by said bracket and having a cam-slot, a shaft for the segment journaled in said bracket, said shaft constituting the lamp-support, a slide-rod guided in said bracket and having a projection engaging said slot, and means for actuating said slide-rod, substantially as described. 75

In testimony that I claim the foregoing I have hereunto set my hand this 22d day of June, 1900.

JOHN WRIGLEY.
